APPARATUS FOR AND METHOD OF MACHINING VALVE WEDGE WITH DISC GRINDER

John Powers Van Steenberg, New York, N. Y.

Application March 19, 1953, Serial No. 343,442

7 Claims. (Cl. 51—125)

The present invention relates to valves and particularly to an apparatus and method for refacing valve wedges with a disc grinder.

It is important that valves used in industrial processes, for steam heating and the like, provide a good seal when in the closed position as, obviously, the wasteage because of fluid leakage through a poor seat may be quite expensive.

Heretofore, valve reseating outfits have been provided of precision manufacture and which generally consist of a large plate equal in diameter to that of the surface to be refaced. A plurality of openings are spaced around the edge of the plate to receive clamping tools adapted to hold hones or cutters on the surface of the plate. Some of the cutters have saw-toothed edges and are alternated with other cutters having a straight cutting edge. Shims are placed under the saw-toothed cutters to roughen the seat after which the shims are removed and the finishing job done using all of the cutters on the plate. In order to prevent digging or roughening of the valve seat, it is important that the plate be fitted with a full set of cutters in proper adjustment. Furthermore, this method of refacing valve wedges can only be done at a slow rate and thus is not practical for a mechanized unit as surface waves and chatter marks appear, particularly when working on seats of the harder metals, such as Monel, stainless steel and Stellite. In fitting the wedge to the body seats, hand scraping or filing had been necessary to provide the proper seating angles for the wedge.

The present invention aims to overcome the difficulties and disadvantages of prior devices by providing an apparatus and a method for refacing valve wedges with a disc grinder and which utilizes equipment generally available in the average tool shop.

Another object of the invention is to provide an apparatus for reseating valve wedges which is simple and economical in manufacture, efficient in operation and durable in use.

Another object of the invention is to provide a method of reseating valve wedges which may be readily learned by the average mechanic and performed rapidly at a low labor cost per valve.

In accordance with the invention this is accomplished by using a readily renewable abrasive disc for the cutting surface to reface the seat. The use of the abrasive disc is advantageous as it is now possible to rapidly reface seats made from stainless steel and other hard metals.

Other objects and advantages of the invention will be apparent from the following description and from the accompanying drawings which show, by way of example, an embodiment of the invention.

In the drawings:

Figure 1 is a side view of a gate valve wedge cutting machine with a wedge in grinding position.

Figure 2 is a top view of the gate valve wedge shown in side view in Figure 1.

2

Figure 3 is a top view of the supporting rotatable table for the abrasive disc.

Figure 4 is an end view of the rotatable table with an abrasive disc in position.

Figure 5 is a vertical sectional view through the rotatable table.

Figure 6 is a vertical sectional view through the gate valve wedge, illustrating the pressure points for varied cutting.

10 Referring to the drawings, there is shown in Figure 1 a gate valve wedge reseating apparatus 1 comprising side frames 2 and 3, a bed frame 4 and a top member or cross frame 5. The bed member 4 carries a bushing member 6 rotatably supporting a shaft 7 carrying a rotatable plate 8. The shaft 7 is driven by beveled gears 9 and 10, gear 10 being at the end of a shaft 11 for a motor 12. An on and off and reversing switch 14 is provided for connection to a source of electrical supply and to provide means for the quick and easy reversal of rotation of the disc 8.

15 The vertical or side frames 2 or 3 are attached to the bed frame by bolts 15 and 16. Likewise, the cross frame 5 is attached to the upper end of the side frames 2 and 3 by bolts 17 and 18. In the center of the cross frame 5 is a bushing member or boss 20 having a threaded inner surface for engagement by a threaded portion 21 of a spindle or point contact member 22, a guiding surface 24 being provided between the threaded and tip portions of the spindle for assuring the alignment of the spindle 22 in the bushing 20. At the top end of the threaded portion 21 is a wheel 25 for upward and downward movement of the spindle 22.

20 A gate valve wedge 30 with its stem 31 is shown in position on the rotatable plate 8. As may be seen in Figure 2, the wedge 30 has a generally circular surface, the seating edge thereof projecting outwardly along the periphery thereof as indicated at 32. In side view as seen in Figure 1, the wedge is made with its bottom end 34 narrower than its top end 35. The wedge member 30 is adapted to be inserted in a gate valve having seating surfaces positioned to be engaged by the seating surfaces 32 of the wedge 30. Leakage of the valve may occur by reason of wear on the surface of either or both the gate valve wedge and its seats in the valve body.

25 As may be seen in Figure 5, the rotatable plate 8 is made with dowel pins 40 and 41 spaced on either side of its center line so as to receive in position one or more laps or alignment discs 42. The alignment disc 42 is made preferably of the same diameter as the periphery of the seat 32 of the wedge 30 with which it is to be used. Thus, the wedge member may be quickly centered in position under the spindle 22 by aligning the edge of the alignment discs with the edge of the wedge. An abrasive disc 44 is attached to the outer surface of the alignment disc 42 by any suitable adhesive or by any other conventional means.

30 After the wedge member is positioned under the alignment disc 42, the spindle 22 is moved downwardly and seated by rotation of the wheel 25. It should be noted that the point of contact of the tip of the spindle 22 with the wedge 30 is not at the center of the top surface thereof, but rather is at a point in axial alignment with the center of the bottom side in contact with the abrasive disc 44. The proper position of the spindle 22 is automatically assumed upon the positioning of the wedge member 30 with its edge in alignment with the alignment disc 42 and will be at the point A of Figure 6. In reseating or refacing the seat 32, the gate valve member is allowed to rotate with the plate 8 until its stem 31 abuts against one or the other vertical frame members 2 or 3 depending upon the rotation of the rotatable plate

8. While the seat may be ground by utilizing a plate 8 having only one direction of rotation, it has been found that certain advantages are obtained by grinding the seat 32 first in one direction and then in the other direction, inasmuch as a flatter surface results, and stock removal is faster. After having been ground to the desired finish, the wedge 30 is then tested by engagement with its seat in the gate body. By the use of bluing or otherwise, the ground surface may be observed for sufficiency of contact. In the event bottom end 34 is slightly too wide, a slight amount of grinding may be done with the point contact member in the position B of Figure 6. By so moving the pressure point of the spindle 22, a somewhat greater grinding speed is had at the bottom end of the wedge, thereby reducing its thickness at a greater rate than is the reduction of the top end 35.

In like manner if the top portion 35 is found to have an excessive thickness, a uniform reduction of the surface may be had greater at the top end 35 by moving the spindle 22 to the position C of Figure 6. In this case an increased rotative speed of the abrasive disc will occur at the top end of the wedge 30 thereby reducing its thickness at a greater rate than at the bottom end 34. However, by reason of the flat surface of the abrasive disc 44, a uniform surface is provided which requires no fitting after the top or bottom ends have been ground to the desired angle.

While it is not often necessary to do so, the spindle 22 may be applied to the upper surface of the wedge member at one or the other sides of the center point A, but along the plane of the point A. This means a correction could be made in the angle of surface of the wedge member to fit a pair of body seats in which one is thicker than the other at the side portions thereof.

While the invention has been described and illustrated with reference to a specific embodiment thereof, it will be understood that other embodiments may be resorted to without departing from the invention. For example, while the alignment disc 42 has been described as being of the same size as the periphery of the wedge 30, the alignment disc may be made larger so as to accommodate wedges of various sizes. In this case centering of the wedge would be accomplished by sighting the centering of the wedge member on the alignment disc. For example, while the rotatable member 8 has been shown as the supporting means for the gate valve member 30, an alternative construction might be had in which the spindle 22 is positioned under the gate wedge member 30 and the rotatable member 8 is positioned at the top thereof. Likewise, the entire assembly might be rotated through an angle of ninety degrees or thereabouts so that the abrasive disc would work in a vertical plane. However, the preferred position is shown with the rotatable plate under the wedge as the more practical construction for most of the wedges. However, for the larger sizes it may be preferable to have the rotatable plate positioned over the wedge. Therefore, the form of the invention set out above should be considered as illustrative and not as limiting the scope of the following claims.

I claim:

1. The method of evenly refacing a gate valve wedge comprising providing a rotating abrasive surface of the same size as the face of the gate valve wedge, centering the wedge over the rotating abrasive surface, urging the gate valve wedge against the rotating abrasive surface, the force being applied to the wedge approximately at a point in axial alignment with the center point of the surface being reseated.

2. The method of evenly refacing a gate valve wedge comprising providing a rotating abrasive surface of the same size as the face of the gate valve wedge, centering the wedge over the rotating abrasive surface, urging the wedge against the rotating abrasive surface, the force being applied to the opposite side of the wedge being re-

seated and at a point in axial alignment with the center point of the surface being reseated.

3. The method of evenly refacing a gate valve wedge by reducing the thickness of the bottom thereof comprising providing a rotating abrasive surface of the same size as the face of the gate valve wedge, centering the wedge over the rotating abrasive surface, and urging the wedge against the abrasive surface, providing a point, and applying force through the point against the top of the wedge in axial alignment with the center point of the surface being reseated.

4. A gate valve wedge refacing apparatus comprising a frame, point contact bearing means carried by the frame, a flat abrasive disc of the same size as the face of the wedge to be refaced, means for rotating the abrasive disc, the abrasive disc carried by the frame with the center of the disc in alignment with the axis of the point contact bearing means, adjustable means to vary the spacing between the point contact means and the abrasive disc, and wedge stop means adapted to hold the wedge against rotation with the disc, the wedge surface adapted to be positioned against the abrasive disc and centered thereon by alignment of the edge thereof, the point contact means adapted to be moved into contact with the other face of the wedge by the adjustable means to hold the wedge in centered relationship with the abrasive disc providing even grinding pressure over the wedge face.

5. A gate valve wedge refacing apparatus comprising a frame, point contact bearing means carried by the frame, a flat abrasive disc of the same size as the face of the wedge to be refaced, reversible means for rotating the abrasive disc, the abrasive disc carried by the frame with the center of the disc in alignment with the axis of the point contact bearing means, adjustable means to vary the spacing between the point contact means and the abrasive disc, and wedge stop means adapted to hold the wedge against rotation with the disc, the wedge surface adapted to be positioned against the abrasive disc and centered, thereon by alignment of the edge thereof, the point contact means adapted to be moved into contact with the other face of the wedge by the adjustable means to hold the wedge in centered relationship with the abrasive disc providing even grinding pressure over the wedge face.

6. A gate valve wedge refacing apparatus comprising a frame, point contact bearing means carried by the frame, a flat abrasive disc of the same size as the face of the wedge to be refaced, means for rotating the abrasive disc, the abrasive disc carried by the frame with the center of the disc in alignment with the axis of the point contact bearing means, adjustable threaded means to vary the spacing between the point contact means and the abrasive disc, and wedge stop means adapted to hold the wedge against rotation with the disc, the wedge surface adapted to be positioned against the abrasive disc and centered thereon by alignment of the edge thereof, the abrasive disc providing the sole support for the wedge, the point contact means adapted to be moved into contact with the other face of the wedge by the adjustable threaded means to hold the wedge in centered relationship with the abrasive disc providing even grinding pressure over the wedge face.

7. A gate valve wedge refacing apparatus comprising a frame including a bed member and a crosspiece extending thereover in spaced relationship, point contact bearing means carried by the crosspiece of the frame, a flat abrasive disc of the same size as the face of the wedge to be refaced, reversible means for rotating the abrasive disc supported by the bed of the frame, the abrasive disc carried by the frame with the center of the disc in alignment with the axis of the point contact bearing means, adjustable threaded means carried by the crosspiece of the frame to vary the spacing between the point contact means and the abrasive disc, and wedge

stop means adapted to hold the wedge against rotation with the disc, the wedge surface adapted to be positioned against the abrasive disc and centered thereon by alignment of the edge thereof, the abrasive disc providing the sole support for the wedge, the point contact means adapted to be moved into contact with the other face of the wedge by the adjustable threaded means to hold the wedge in centered relationship with the abrasive disc providing even grinding pressure over the wedge face.
